SWITCH POINT INDICATOR FOR RAILWAY TRAFFIC CONTROLLING SYSTEM CONTROL PANELS

Carlton T. Jackson, Conesus, N.Y., assignor to General Railway Signal Company, Rochester, N.Y.

Filed Mar. 21, 1957, Ser. No. 647,678

3 Claims. (Cl. 246—162)

This invention relates to control and indication panels for railway centralized traffic control systems, and more particularly relates to a track switch point indicator for use on such panels.

In the usual type of railway traffic control system, the remote switches and signals are controlled by a control machine located at a central point in the system. The control machine is provided with a control panel having a track layout suitably engraved thereon with the necessary control buttons, signal lights and track switches appropriately located to simulate the actual track layout being controlled. Upon operation of the control buttons to set up a certain train route, the remote track switches are operated accordingly and indications are received back at the control point which operate the electro-magnetic switch point indicators on the control panel to correspond to the position of the actual remotely located track switches.

Such a control panel must of necessity be miniature in size. This requires an electro-magnetic switch point indicator of small compact size which is reliable and durable in operation.

The present invention proposes an electro-magnetic structure which operates a rotatable armature to either one of two extreme positions. This magnetic structure is fastened to the back of the panel. The indicating arms of the switch point indicator are located on the front of the panel where they are visible to the operator. They are positioned within and coact with the engraved or grooved track layout to form a track route in accordance with their operated positions. These indicating arms are an integral part of a cylindrical bearing portion, the arms extending radially therefrom. The cylindrical bearing portion is hollow and extends through an opening in the panel where it is connected to the rotatably mounted armature. Thus, any movement of the armature is transmitted to the indicating arms and is visual to the operator who will know the exact position of the track switch. The extent of armature travel is determined by the movement of the indication arms which come to a stop when they bear against the edges of the grooved track layout in their extreme operated positions.

The present invention also proposes an internally mounted indicator lamp whose light beam is visible in a specified color on the front of the panel, located in the center of the indicating arms. This light beam is transmitted through a translucent rod and a color glass which are positioned in the hollow cylindrical bearing portion of the indicating arm assembly. This indicator lamp may be used for any suitable purpose, but primarily it is used to indicate that, when lighted, that particular track switch is in use as part of the track route already set up. Thus, the operator, when setting up another track route, can readily see which part of the track layout is already in use for other track routes.

In the electro-magnetic structure of the present invention, the periphery of the magnetically cooperating surfaces of the pole pieces and the armature is circular in

2

shape; and, they are positioned in relation to each other so that the airgap between a pole piece and the cooperating portion of the armature is at its maximum when that particular pole piece is deactivated. When a particular pole piece is activated, the magnetic pull between that pole piece and the cooperating portion of the armature produces a rotational effort to cause the armature portion to move towards coincidence with that pole piece, and as it does so the rotative effort is reduced and thus the velocity of the armature is reduced. In addition, the cooperating portion of the armature tends to move slightly beyond the position of minimum air gap which tends to produce a reverse rotative effort to further reduce the velocity of the armature as it rotates into its final stop position.

Other objects, advantages and characteristic features of the invention will be brought out as the description thereof progresses. Reference will be made to the accompanying drawings wherein like parts are referred to by like reference characters and in which:

Fig. 1 is a front elevational view of a portion of a typical control panel showing a partial track layout with switch point indicators of the present invention applied thereto;

Fig. 2 is a top view of the switch point indicator of the present invention with the top plate partially broken away to show other parts in full and cross section;

Fig. 3 is a front end view of the switch point indicator of the present invention with parts shown in section and taken substantially on the line 3—3 of Fig. 2;

Fig. 4 is a sectional side elevation of the switch point indicator of the present invention showing the magnetic structure and taken substantially on the line 4—4 of Fig. 2;

Fig. 5 is a sectional side elevation of the switch point indicator of the present invention showing the mounting for the indication lamp, the armature and the indicator arm assembly and taken substantially on the line 5—5 of Fig. 2;

Fig. 6 is a back end view of the switch point indicator of the present invention with parts broken away and parts in section to clarify the showing;

Fig. 7 is a top view of the indication lamp and mounting means with parts being broken away and in section for clearness; and

Fig. 8 is another partial view of the control panel track layout showing a switch point indicator assembled for operation on a crossover which is located in a direction opposite to the crossover shown in Fig. 1.

Referring now more particularly to Fig. 1, there has been shown a section of a typical control and indication panel P which is made from black insulation board. Grooves are cut in the panel P to simulate a track layout which consists of two main tracks 11 and 12 and a siding 13. Grooves are also cut in the panel to simulate a crossover between the tracks 11 and 12 and an entrance from the track 12 to the siding 13. The base of each of these grooves is painted white so that the track layout stands out against the black background.

A switch point indicator S1 constructed in accordance with the present invention and having two indicating arms is mounted on the panel P at a crossover point; whereas, a switch point indicator S2 having one indication arm is mounted on the panel P at a siding entrance point. These indicator arms lie within the grooved sections of the panel P and are operable to either a closed switch position as shown in full lines or an open switch position as shown in dotted lines.

Referring now more particularly to Figs. 2 to 6 inclusive, the switch point indicator assembly comprises a yoke 15 of suitable magnetic material, the top flat portion of which terminates at one end into two right-angle

leg portions 16. A front plate 17 of suitable non-magnetic material such as aluminum, is fastened to the other end of the yoke 15 by means of screws 18 to form a framework of substantially inverted U-shape (see Fig. 4). Two cores 19 are respectively mounted on the two legs 16 by means of screws 21. An energizing coil 23 is suitably mounted on each of the cores 19 and is held in position by the split rings 24. A circular pole piece 20 of suitable magnetic material is adjustably mounted on each of the cores 19. Each pole piece 20 has a circular hole slightly off center which hole permits it to be eccentrically mounted over the end of its core 19, the end portion 38 of which is reduced in cross section. A screw 22 is inserted through a hole in plate 17 and passes through the off-center hole of the pole piece 20 to cooperate with threads in the associated core 19. The screw 22 can then be tightened to firmly hold pole piece 20 between the shoulder on core 19 and the plate 17.

The front plate 17 is provided with an integral upturned angular bracket 25, thus forming a U-shaped structure with two spaced side walls (see Fig. 5). These two side walls are provided with bushings 26 located in openings disposed directly opposite each other. These bushings are preferably made of nylon, Teflon or some other suitable material having a low friction constant. The two spaced bushings 26 form bearing surfaces for a hollow shaft 27 which extends through the two side walls and carries an armature member 28.

The indicator arm structure comprises a hollow cylindrical main portion 29 having arms 30 extending radially therefrom. The cylindrical portion 29 is mounted within the hollow shaft 27 in a manner whereby it rotates with the armature 28. In assembly, the armature 28 is held in position between the two side walls formed by the bracket 25 and the front plate 17 and the hollow shaft 27 is slid into position, passing through the two bushings 26 and a hole in the armature 28. The main assembly is now fastened to the panel P (indicated by dot and dash lines) by means of screws 31 which pass through the panel P from the front side and thread into the front plate 17. The indicating arm structure 29-30 is now inserted through a hole in the panel P from the front side into the hollow shaft 27. A set screw 32, threaded into the bottom section of the armature 28, passes through a hole in the hollow shaft 27 and clamps against the cylindrical portion 29 of the indicating arm assembly. It can now be seen that the armature 28 and the indicating arm assembly 29-30 are securely fastened together and are mounted for rotation on the hollow shaft 27.

Referring now more particularly to the magnetic structure of the switch point indicator, as shown in Fig. 3, the armature 28 has an upper arcuate surface 35 for magnetic cooperation with an arcuate portion of the yoke plate 15, and also two lower arcuate surfaces 36 for magnetic cooperation with the two pole pieces 20. The yoke plate 15 is provided with an arcuate groove 37 therein which forms a path of travel for the armature surface 35, a very small airgap appearing therebetween. The body of the armature member 28 forming the arcuate surface 35 is so constructed that the movement of the armature 28 does not materially change the magnetic reluctance of the path for flux through the small airgap between surface 35 and yoke plate 15. The lower arcuate surfaces 36 are located in a position to be attracted by their respective pole pieces 20 when their respective coils 23 are energized. However, the body of the armature member 28 is so shaped to form the two lower arcuate surfaces 36 as to provide a flux path to either of the pole pieces 20 to cause a high initial rotational torque; but formed so that the armature movement toward either position will cause some of the magnetic flux to be transferred to a path to the respective pole piece 20 located beyond a line 33 drawn from the point of minimum airgap to the center of the armature. This creates a reverse

pull and slows the armature movement as it comes to rest in its new position. Thus, the holding torque for either position is actually lower than the initial torque on the armature. The relatively high initial torque is useful for overcoming its static friction and causing its initial movement toward its new position.

The pole pieces 20 are eccentrically mounted on the cores 19 so that the airgap between the pole pieces 20 and the arcuate surfaces 36 of the armature 28 may be varied by turning the pole piece 20 on its core 19. As previously stated, these pole pieces 20 are mounted on a reduced end portion 33 of the cores 19 (see Fig. 4). The reduced end portion 33 forms a shoulder and the pole piece 20 is clamped between this shoulder and the front plate 17 when the screw 22 is drawn tight. The adjustment of the air gap is facilitated by loosening the screw 22 and turning the pole piece 20 by means of an appropriate tool which is inserted into one of the cross drilled holes 39 in the pole piece 20.

When in operation, the switch point indicator is positioned in either one or the other of its extreme operated positions depending upon which of the two coils 23 is energized. As viewed in Fig. 3, the left-hand coil 23 has been energized causing its pole piece 20 to attract the armature 28 thereto, thus causing the armature to rotate in a clockwise direction to its left-hand position as shown. The magnetic path formed by the flow of flux induced in the core 19 includes the core 19, pole piece 20, armature 28 and the yoke plate 15. This movement of the armature 28 has caused a movement of the indicator arms 30 to a closed switch position as shown in Fig. 1 and the track routes are lined up for through movements on both tracks 11 and 12. As previously mentioned, these indication arms 30 lie in a cut out groove portion of the panel P and the extent of their movement is thus limited. This limited movement of the indication arms 30 provides stops for the armature 28. This stopping point is determined when the tip of the indication arms 30 comes into contact with the edge of the grooves cut in the panel P, as shown at the points 40. Similarly, the energization of the right-hand coil 23 causes a reverse movement of the indication arms 30 to an open switch position as shown in dotted lines. The armature movement will of course stop when the tip of the indication arms 30 comes into contact with the other edge of the panel grooves as shown at the points 41.

When the operator sets up a track route for a cross-over movement from one track to another which calls for switch movements, the switch point indicator S1 would react accordingly and the indicator arms 30 on the panel P would move to an open switch position as shown by the dotted lines in Fig. 1. This movement would occur because the indication circuit would cause the left-hand coil 23 to be deenergized and the right-hand coil 23 to be energized. With the right-hand coil 23 energized, the flow of flux in its associated core 19 would cause movement of the armature 28 in a counterclockwise direction to its right-hand position.

With reference again to the magnetic structure, particularly to the operation of the armature as shown in Fig. 3 the location of the two pole pieces 20 and the armature 28 with respect to each other, along with their particular shapes, provides a structure having certain advantages in operation. As can be seen, the periphery of the pole pieces 20 is circular and the periphery of the two armature cooperating surfaces 36 is circular. With the armature 28 in its extreme clockwise position as shown, the airgap between the right-hand armature surface 36 and right-hand pole piece 20 is at its maximum.

When the activating flux is built up in the magnetic structure, the right-hand pole piece 20 will attract the armature surface 36 thereto, causing the armature 28 to rotate in a counter-clockwise direction (see Fig. 3). Due to the strong magnetic pull required to initiate the armature motion and due to the decreasing airgap, accelera-

tion of the armature movement would tend to be very rapid. But, since the rotation of the armature reduces the angle through which the magnetic pull is acting, the net rotative effort is reduced. As rotation of the armature progresses, the airgap between the armature surface 36 and the surface of the pole piece 20 soon reaches its minimum spacing. Furthermore, as the leading edge of the armature surface 36 passes the center of the arc (indicated by the line 33) on the periphery of the pole piece 20, the armature area on that side of center starts to increase, thus creating a reverse magnetic pull which additionally tends to brake the armature. The net result is that when the armature 28 reaches its stop position, which in this case is determined when the indicating arms 30 reach the side of the groove in the panel P, the stopping impact is considerably reduced.

The indication lamp L is mounted in a rectangular block of insulation 45 which is mounted to the underside of the yoke plate 15 by means of screws 46 (see Figs. 5 and 6). This insulation block 45 is provided with a transverse hole 47 therethrough which is in alignment with the hollow cylindrical portion 29 of the indicator arm assembly. Resilient contact springs are fitted one to each side of the insulation block 45 for the purpose of holding the lamp L in position and completing the lamp circuit. These contact springs have an arched portion 48 lying within the transverse hole 47 and a finger portion 49 which extends to the rear to facilitate wiring connections.

The lamp L is of the conventional panel mounting type having a base 51 of insulation and two metallic finger clips 52 which are connected to the lamp filament and extend along the sides of the lamp envelope. When the lamp L is inserted into the transverse hole 47 in the insulation block 45, the two metallic finger clips 52 slide between the two arched portions 48 of the contact spring, thus compressing the spring portions 48. This spring bias contacting means holds the lamp L in position and completes the circuit through the lamp filament.

The hollow cylindrical portion 29 of the indicating arm assembly provides a housing for a light transmitting rod 55 made from "Lucite" or some other suitable type of light conducting material (see Fig. 5). This light transmitting rod 55 is slid into position from the front side of the panel P and is reduced in diameter at its panel end to accommodate a color glass retainer 56. This retainer 56 is cylindrical in form and has a ring 57, with a color glass insert 58 therein, mounted in its outside end. The other end is provided with biased spring fingers 59. When the retainer 56 is pushed into place over the reduced portion of the light transmitting rod 55, the bias of the spring fingers 59 holds it in place. Thus, the light beam from the lamp L is efficiently transmitted through the light transmitting rod 55 to the color glass insert 58 where it is visible on the front of panel P.

A terminal board 65 of insulation material is mounted across the two leg portions 16 of the top plate 15 to facilitate external wiring connections. This terminal board 65 is held in place by the same two screws 21 which hold the cores 19. Suitable terminal posts 66 in this terminal board 65 provide a connecting means between the wires from the coils 23 and the external wiring. The contact fingers 49 from the indication lamp L extend through holes 67 to a point where external wiring connection may be made.

The provision of an indication lamp whose indication is displayed wholly within the switch point indicator device as shown and described herein is considered very advantageous for use on control and indication panels for railway traffic controlling systems.

The switch point indicator of the present invention may be used on the panel to indicate various switch locations such as are used on crossovers and sidings in either direction, the only requirement being that different indicating arm assemblies are used to fit the track condition. For

example, in Fig. 1 there has been shown a switch point indicator S1 having an indicating arm assembly wherein the indicating arms 30 are located in the upper right-hand corner and the lower left-hand corner to correspond to a track layout having a crossover from track 11 in a left-hand direction to track 12.

In Fig. 8, there has been shown a track layout having a crossover from track 11 in a right-hand direction to track 12 and the switch point indicator S3 has its indicating arms 30 located in the upper left-hand corner and the lower right-hand corner. Also in Fig. 1 there has been shown a switch point indicator S2 located at the entrance to the siding track 13 for traffic in a left-hand direction. As only one switch is required in the track layout, only one indication arm 30 is necessary on the panel layout, this being located in the upper right-hand corner. If the entrance to the siding was in a right-hand direction, the indicating arm 30 would be in the upper left-hand corner to correspond to the track layout. The switch point indicators are provided with multiple mounting holes so that the mounting screws 31 may always be located under the indicating arms 30 where they are not visible.

It should also be understood that the switch point indicator arms stay in their last operated positions if both their coils become deenergized.

Having thus shown and described one specific form which the present invention can assume and the manner in which it can be used, it should be understood that various other adaptations, modifications, and alterations could be made in the structure, all without departing from the spirit or scope of the present invention, except as limited by the appending claims.

What I claim is:

1. A movable switch point indicator for a track diagram on a panel comprising, two laterally spaced U-shaped electromagnetic structures, each of said structures having a pole piece at the same end of one leg thereof, a yoke of magnetic material connecting the other legs of said U-shaped magnetic structures, said yoke having an arcuate surface in a portion between the two magnetic structures, an armature pivotally disposed adjoining said arcuate surface of said yoke and said pole pieces having a plurality of arcuate surfaces in its periphery, one of said surfaces being adjoining the arcuate portion of said yoke and other of said arcuate surfaces of said armature being adjoining the pole pieces of the two laterally disposed U-shaped electromagnetic structures, and a pointer indicative of a switch point in the track diagram secured to said armature so as to be rotated thereby, whereby energization of one of said electromagnetic structures rotates said pointer in one direction by passage of flux through said armature from said yoke to one of said pole pieces and the energization of the other of said electromagnetic structures rotates said pointer in the other direction by the passage of flux through said armature from said yoke to the other of said pole pieces.

2. A movable switch point indicator according to claim 1 wherein said pole pieces are circular in shape and each of the pole pieces has a point on its periphery which is adjoining an associated arcuate surface on said armature.

3. A movable switch point indicator according to claim 2 wherein each of said pole pieces is eccentrically pivoted to permit adjustment by rotation of an air gap between a point on the periphery of that pole piece and an adjoining arcuate surface on said armature.
